ATTORNEY.

UNITED STATES PATENT OFFICE.

ALBERT WANNER, JR., OF NEW YORK, N. Y.

DESIGN FOR A FOLDING CHAIR.

48,955.

Specification for Design.

Patented Apr. 25, 1916.

Application filed December 20, 1915. Serial No. 67,919. Term of patent 14 years.

To all whom it may concern:

Be it known that I, ALBERT WANNER, Jr., a citizen of the United States, residing in the borough of Manhattan, city and State of New York, have invented a new, original, and ornamental Design for a Folding Chair, of which the following is a specification, reference being had to the accompanying drawing, forming a part thereof.

The figure is a perspective view of the folding chair showing my new design.

The pair of uprights *a a* are connected near and above the seat *b* by the horizontal

cross-piece *c* inset between said uprights; superimposed upon their upper ends is the vertically broad flat back top-piece *d* curved in plan and having its concave side facing forward, each of the parts *a*, *c* and *d* being angular in cross-section, and the parts *a a* being tapered upwardly and the part *d* having its lateral edges upwardly divergent.

I claim:

The ornamental design for a folding chair, substantially as herein described and shown.

ALBERT WANNER, JR.
